AERIAL AND FEEDER SYSTEM FOR USE IN HIGH FREQUENCY SIGNALING SYSTEMS

Edward Cecil Cork, Ealing, London, and Joseph Lade Pawsey, Hillingdon, England, assignors to Electric & Musical Industries Limited, Hayes, Middlesex, England, a company of Great Britain

Application June 24, 1937, Serial No. 150,030
In Great Britain July 10, 1936

11 Claims. (Cl. 250—33)

This invention relates to high frequency signaling systems and has particular reference to short wave aerial and feeder systems employing frequencies of the order used for television transmission. The invention is also applicable to aerials used in the reception of signals.

In such systems it is common practice to use an aerial consisting of a tuned half wavelength of wire conductor fed at one end from a transmitter. The impedance of such an aerial at the feed point is usually of the order of two thousand ohms while the characteristic impedance of a concentric feeder connecting the aerial with the transmitter connecting the aerial with the transmitter may in such a case be of the order of one hundred ohms. It is accordingly necessary to employ some means for matching these impedances and transformer devices are commonly employed for this purpose. In the case specified a high ratio of transformation viz: twenty to one is involved. A well known type of transformer for this purpose is disclosed in the specification of British Patent No. 282,905, or again, a tuned coil with an adjustable tapping point may be used.

The types of impedance matching device previously proposed introduce considerable selectivity and constitute additional means requiring adjustment.

It is the object of the present invention to provide an impedance matching arrangement which does not introduce undesirable selectivity.

According to the present invention, the physical dimensions of an aerial of which the electrical length is equal to or approximately equal to an integral number of half-wavelengths of the carrier frequency radiated or received are made such that the ratio between the open-ended impedance of the aerial and the characteristic impedance of the aerial or other circuit connected with the aerial is not greater than 4:1.

In carrying the invention into practice it is preferred to match the impedance of the aerial with that of the feeder or other circuit connected with it so that the use of a separate transformer can be dispensed with. However, even if a separate transformer is used, as the ratio of transformation will be low, it is less difficult to obtain a transformer which will pass a sufficiently wide band of signal frequencies such as is required to be passed in a television transmitter.

In order that the invention may be clearly understood and readily carried into practice, a short wave transmitting aerial constructed in accordance therewith will now be described by way of

example with reference to the accompanying drawing, in which:

Fig. 1 is a diagrammatic representation of certain electrical characteristics of an aerial and

Fig. 2 shows diagrammatically a particular form of aerial.

Referring to Fig. 1 of the drawing, A, B represents a tuned half wave aerial and r is a resistance which represents the series radiation resistance of the aerial, assumed to be concentrated at the centre.

If Z_{0A} is the characteristic impedance of the aerial, the resistance R at the point A is given by the equation:

$$R = \frac{Z_{0A}^2}{r}$$

Assuming that it is desired to match the aerial to a feeder of characteristic impedance Z_{0F} , this can be done by making

$$Z_{0F} = \frac{Z_{0A}^2}{r}$$

from which

$$Z_{0A}^2 = rZ_{0F}$$

The characteristic impedance Z_{0A} of the aerial is determined by the diameter of the aerial conductor and in the case of a circular cylinder of radius a ,

$$Z_{0A} = \left(\log_{10} \frac{\lambda}{2\pi a} - 0.25 \right)$$

In the case of a feeder having a characteristic impedance Z_{0F} of seventy eight ohms, connected to a circular aerial having a characteristic impedance Z_{0A} of seventy-four ohms and a series resistance r of seventy ohms, the wavelength λ to be used being 6.5 metres, the radius a of the aerial should be 6.7 inches.

Referring to Fig. 2 of the drawing a half-wave dipole aerial A, B is connected at its lower end to the inner conductor C of a concentric feeder F. A centre tapped half wave conductor X, Y effectively earths the ends of the outer sheath of the conductor F for the working frequency and a similar conductor X¹, Y¹, serves the purpose of further suppressing waves on the outside of the sheath.

The aerial conductor itself may consist of a tube of metal or wire gauze, a large strip of metal or a number of wires in parallel, or in fact any conducting surface, the dimensions of which may be modified in accordance with the invention. In the case of a metal or gauze tube, the required

dimensions may be calculated as explained with reference to Fig. 1. In other cases, it may be necessary to resort to experiment. Thus in a particular example, an aerial consisting of eight parallel wires arranged in the form of a cylinder having a radius of about seven inches, was found to have a measured resistance of one hundred and eighty ohms and a characteristic impedance estimated at about one hundred ohms. Increase of 10 the diameter of the aerial in this case would evidently permit considerable decrease in its resistance.

If the open-ended impedance of the aerial is made low enough to match the characteristic impedance of the feeder, as above described, the use of a transformer between the aerial and feeder is unnecessary. However, satisfactory results according to the invention, may be obtained even when the characteristic impedance of the aerial 20 is not more than four times as great as the latter. In this case, as is well known, transformers with the required small ratio of transformation, (approximately 2.1) can be readily obtained, which do not have an objectionably high selectivity.

We claim:

1. An aerial having a feeder connected thereto, said aerial having an electrical length equal to an integral number of half wavelengths of the 30 carrier frequency to which the aerial is tuned, said aerial having substantially a cylindrical form for a substantial portion of its length which tapers into substantially a conical form whose apex is connected to said feeder, the diameter of 35 said aerial being such that the ratio between the open-ended impedance of the aerial and the characteristic impedance of said feeder is not greater than 4:1.

2. An aerial having a feeder connected thereto, 40 said aerial having an electrical length approximately equal to an integral number of half wavelengths of the carrier frequency to which the aerial is tuned, said aerial having substantially a cylindrical form for a substantial portion of its length which tapers into substantially a conical form whose apex is connected to said feeder, the diameter of 45 said aerial being such that the ratio between the open-ended impedance of the aerial and the characteristic impedance of said feeder is not greater than 4:1.

3. A high frequency signal transmitting system comprising in combination transmitting apparatus, a feeder and an aerial connected with said transmitting apparatus by said feeder, said aerial having an electrical length equal to an integral 55 number of half wavelengths of the carrier frequency to which the aerial is tuned, said aerial having substantially a cylindrical form for a substantial portion of its length which tapers into substantially a conical form whose apex is connected to said feeder, the diameter of 60 said aerial being such that the ratio between the open-ended impedance of the aerial and the characteristic impedance of said feeder is not greater than 4:1.

4. A high frequency signal receiving system comprising in combination signal receiving apparatus, a feeder and an aerial connected with said receiving apparatus by said feeder, said aerial having an electrical length equal to an integral 70 number of half wavelengths of the carrier frequency to which the aerial is tuned, said aerial having substantially a cylindrical form for a substantial portion of its length which tapers into substantially a conical form whose apex is connected to said feeder, the diameter of 75 said aerial

being such that the ratio between the open-ended impedance of the aerial and the characteristic impedance of said feeder is not greater than 4:1.

5. An aerial having a feeder connected thereto, 5 said aerial having an electrical length equal to an integral number of half wavelengths of the carrier frequency to which the aerial is tuned, the physical dimensions of said aerial being such that the ratio between the open-ended impedance of the aerial and the characteristic impedance of 10 said feeder is not greater than 4:1, said aerial having a diameter such that the relation

$$Z_{0A} = \sqrt{r Z_{0F}}$$

is at least approximately true, where Z_{0A} is the 15 characteristic impedance of the aerial at the frequency of the carrier wave radiated, r is a resistance which represents the series radiation resistance of the aerial, assumed to be concentrated at the center thereof, and Z_{0F} is the characteristic impedance of the said feeder or other circuit at the frequency of the carrier wave radiated.

6. A short wave aerial according to claim 1 and composed of a group of parallel wires arranged 25 in the form of a cylinder.

7. An aerial system for the transmission or reception of a wide band of short waves, comprising an aerial having connected thereto a feeder, 30 said aerial having a diameter such that the relation

$$Z_{0A} = \sqrt{r Z_{0F}}$$

is approximately true, where Z_{0A} is the characteristic impedance of the aerial at the frequency 35 of the carrier wave to be radiated or received, r is the resistance which represents the series resistance of the aerial, assumed to be concentrated at the center thereof, and Z_{0F} is the characteristic impedance of said feeder at the frequency of said 40 carrier wave.

8. An aerial system in accordance with claim 7, characterized in this that said feeder is a concentric feeder whose inner conductor is connected to one end of said aerial and whose outer conductor 45 is effectively grounded for the operating frequency at the end adjacent said one end of said aerial.

9. An aerial system for the transmission or 50 reception of a wide band of short waves, comprising an aerial having connected to one end thereof a section of concentric transmission line, the inner conductor of said concentric line being connected to said aerial, the lower portion of said aerial which connects with said inner conductor 55 being in the form of a cone, said aerial having a diameter such that the relation

$$Z_{0A} = \sqrt{r Z_{0F}}$$

is approximately true, where Z_{0A} is the characteristic impedance of the aerial at the frequency 60 of the carrier wave to be radiated or received, r is the resistance which represents the series resistances of the aerial, assumed to be concentrated at the center thereof, and Z_{0F} is the characteristic impedance of said feeder at the frequency of said carrier wave, and means for effectively grounding the outer conductor of said line for the working frequency.

10. An aerial system for the transmission or 70 reception of a wide band of short waves, comprising an aerial having connected to one end thereof a section of concentric transmission line, the inner conductor of said concentric line being connected to said aerial, the lower portion of 75

said aerial which connects with said inner conductor being in the form of a cone, said aerial having a diameter such that the relation

$$Z_{0A} = \sqrt{rZ_{0F}}$$

5 is approximately true, where Z_{0A} is the characteristic impedance of the aerial at the frequency of the carrier wave to be radiated or received, r is the resistance which represents the series resistance of the aerial, assumed to be concentrated at the center thereof, and Z_{0F} is the characteristic impedance of said feeder at the frequency of said carrier wave, and a half wave conductor connected at its center to the end of the outer 10 conductor adjacent said aerial for effectively grounding said outer conductor for the working frequency.

11. An aerial system for the transmission or reception of a wide band of short waves, comprising a circular cylindrical aerial having a feeder connected thereto, said aerial having a diameter such that the relation

$$Z_{0A} = \left(\log_{10} \frac{\lambda}{2\pi a} - 0.25 \right)$$

15 is approximately true, where Z_{0A} is the characteristic impedance of the aerial at the frequency of the carrier wave to be radiated or received, λ the wavelength of the carrier wave, and a is the radius.
